UNITED STATES PATENT OFFICE.

CHARLES I. EVANS, JR., OF DALLAS, TEXAS.

CARBON-GRIPPER AND MARGIN-INDICATOR FOR WRITING-MACHINES.

1,173,345.

Specification of Letters Patent.

Patented Feb. 29, 1916.

Application filed October 15, 1915. Serial No. 56,061.

To all whom it may concern:
Be it known that I, CHARLES I. EVANS, Jr., a citizen of the United States, residing at Dallas, in the county of Dallas and State 5 of Texas, have invented a new and useful Carbon-Gripper and Margin-Indicator for Writing-Machines, of which the following is a specification.

My invention relates to improvements in 10 devices for handling, securing and carrying paper, both carbon and writing paper, in typewriting machines, during the time the same is passing through and after the same has passed through the paper feed cylinder 15 or platen of such machines, which consist of a metal frame and parts thereof, attached to or made as a part of the paper table on typewriting machines commonly and generally known by the following names: Underwood typewriter, all models; Remington typewriter, all models; Fox typewriter, all 20 models; L. C. Smith & Bro. typewriter, all models; Remington Monarch typewriter, all models; Royal typewriter, all models; Oliver typewriter, all models; and all other typewriting machines to which the device 25 may be attachable, the same device to be used on all of the above mentioned typewriting machines, except that the means of attachment to the paper table will be varied so as 30 to make it adaptable to each kind of typewriting machine.

The objects of my improvement are: First. To present to the view of the typewriter operator the full page of typewritten matter, as rapidly as the same may be written, thereby making the reading matter on each page visible as the same is written. Second. To indicate with certainty to the 40 eye of the operator the approach of the bottom margin of the paper upon which the writing is done, and to secure uniformity in said margin. Third. To secure in position and prevent from displacement sheets 45 of carbon paper when being used between sheets of writing paper for the purpose of making manifold copies. Fourth. To indicate with approximate certainty and to secure uniformity of the top margin of 50 paper when inserted in the paper feed cylinder or platen of the typewriting machine.

Fifth. To provide means by which the hinged arms of the device may be opened to receive and discharge paper.

I attain these objects by the mechanism 55 illustrated in the accompanying drawing, in which:

Figure 1 is a front elevation of the device, with the guide members folded. Fig. 2 is a side elevation of the device for clamp- 60 ing the paper holder on the paper table of the typewriting machine. Fig. 3 is a front elevation of the paper holding device mounted on the writing machine paper table. Fig. 4 is a cross section of one of the 65 side frame pieces. Fig. 5 illustrates a variation in the means for mounting the paper holder on the paper table of the writing machine.

The same characters of reference are used 70 to indicate same parts throughout the several views.

The paper holder has a frame composed of side-bars 1 and 2, with a cross-bar 3 at the upper side. This frame is mounted on the 75 paper table of a typewriting machine by means of clamping members 4, and a pivoted member 5, which is pivoted or connected to the member 4 by an upstanding tongue 6, which is formed on the member 5 and by the 80 lips 7, which are formed on the member 4. The typewriter paper table is received between the forward ends 8 of the clamping members, and the clamping members are secured to the paper table by means of a 85 thumb screw 9. The ends of the frame members 1 and 2 are received in sockets formed on the member 4. The clamping member shown in Fig. 2 must be varied to engage the paper table on the different types of 90 writing machines to set the holding member at the proper angle in front of the operator, and this angle should be approximately forty-five degrees. The ends of the frame members 1 and 2 may be made cy- 95 lindrical at 11 for the purpose of entering the sockets 10. If preferable the side mem- bers 1 and 2 may be integral with the sockets 10 and the members 4. If desired the clamping members will not be used in at- 100 taching the device to the writing machine known as the Remington No. 6, but the ends

of the frame members 1 and 2 are to be inserted directly in the sockets provided on said machine for the reception of the legs of the paper table of said writing machine.

5 The paper holder is provided with swinging guide arms which are pivotally connected to the lateral arms 12 projecting from the sides of the frame members 1 and 2. The swinging guide members consist of bars 13, provided with bent arms 14, which are hingedly connected to the arms 12. The lateral arms 12 are drooped more or less, and the arms 14 have shanks 15 which reach down to the arms 12, the object being to provide 15 plenty of space between the arms 12 and 14 for the movement of the paper, so that the edges of the paper will not be caught against the arms.

20 The lower end 16 of the guide members are to be curved outwardly or upwardly sufficiently to receive the paper when the paper is being fed back on to the holder, after having passed through the paper feed cylinder or platen of the typewriting machine.

25 The guide members 13 lie loosely on the paper without pressure, and will not necessarily touch the paper, unless there are many sheets of paper. The guide members 13 may be swung outwardly as shown in Fig. 3, for 30 the purpose of receiving the paper when first placed on the machine. When the paper is to be removed from the holder the guide members are so light and so easily movable that the withdrawal of the paper 35 will swing them outwardly automatically. After the paper is placed on the frame members 1 and 2 and the cross members 17 the guide members 13 may be swung back over and on top of the paper for preventing the 40 paper from being thrown or blown out of place as the writing is being done. The guide members are particularly useful when manifold copies are being made with carbon paper, because all of the sheets of paper 45 and carbon sheets of paper will be held safely in place, without entangling the sheets or creasing the same, as well as preventing the sheets of paper from being displaced by air currents. The frame members 50 1 and 2 may be provided with spacing devices 18, which are movable, for conveniently locating and definitely indicating the approach of the bottom margin, after the paper has passed through the platen of the 55 writing machine. A movable marker 19 may be mounted on either frame 13 of the guide member for conveniently spacing and indicating the top margin, and making the top margin uniform.

60 Various changes may be made in the sizes and proportions of the various parts of the paper holder without departing from my invention.

65 The variation shown in Fig. 5 consists of tubes or sockets 20, which may be inserted in

or made as a part of paper table 21 of the writing machine, and constitute sockets to receive the shanks 11 of the frame pieces 1 and 2. The tubes 20 may be attached to the typewriter paper table in any suitable manner, or the tubes may be made as a part of the paper table, the object being to provide some holding device from which the paper holder may be readily detached.

What I claim is:

1. In a writing machine provided with a paper table; a gripper and indicator mounted on said table and consisting of a flat paper-supporting frame and guide members hingedly connected to the sides of said frame 75 and adapted to swing over the edges of and to stand out of the plane of said frame in close proximity thereto.

2. In a writing machine provided with a paper table; a gripper and indicator mounted on said table and consisting of a flat paper-supporting frame provided with lateral arms and guide members provided with arms hingedly connected to said first mentioned arms and adapted to swing over the 85 edges of and to stand out of the plane of said frame in close proximity thereto.

3. In a writing machine provided with a paper table; a gripper and indicator consisting of a flat paper-supporting frame, clamping members for attaching said frame to said table, and guide members hingedly connected to said frame and adapted to swing over the lateral edges of said frame and stand out of the plane of said frame in close 95 proximity thereto and easily movable by the sheet or sheets of paper when being removed from said frame.

4. In a writing machine provided with a paper table; a gripper and indicator comprising a flat frame provided with lateral arms, clamping members for mounting said frame on said table, guide members hingedly connected to said arms and adapted to swing over the sides of said frame and stand in 105 close proximity thereto, and arms rigidly connected with said guide members having bent shanks hingedly connected to the arms of said frame.

5. In a writing machine provided with a paper table; a gripper and indicator comprising a flat frame provided with lateral arms, clamping members for mounting said frame on said table, guide members, lateral arms rigid with said guide members and having bent shanks and hinges connecting said shanks to the arms of said frame and having shoulders to hold said guide members out of the plane of said frame.

6. In a writing machine provided with a paper table; a gripper and indicator comprising a flat frame provided with lateral arms, guide members having lateral arms hingedly connected to the arms of said frame, clamping members for attaching said 125 130

frame to said table, and indicating devices mounted adjustably on one of said guide members.

7. In a writing machine provided with a paper table; a gripper and indicator comprising a frame set at an angle on said table for supporting sheets of paper, and swinging guide members hingedly connected to said

frame and adapted to swing over the sides of said frame and stand out of the plane of 10 said frame in close proximity thereto, said guide members having the lower ends thereof curved outwardly to receive the sheets of paper when entering the writing machine.

C. I. EVANS, JR.
